HEARSE HAVING REVERSIBLE CASKET
TABLEAnthony M. Schneider, Detroit, and Jules A.
Olivier, Grosse Pointe, Mich.

Application November 15, 1949, Serial No. 127,302

6 Claims. (Cl. 296—16)

1

This invention relates to a hearse construction and more particularly to a track arrangement for a side service type of hearse.

A hearse having a door opening at each side as well as at the rear for removal of a casket is commonly referred to as a side service hearse. Side service hearses of conventional construction are provided with a casket table in the casket compartment and a track arrangement for the table which permits movement of the table so that its front end may be guided to a position projecting outwardly through the door opening at either side of the hearse. The track also enables the table to be moved rearwardly to permit removal of the casket from the rear end of the hearse. However use of the rear door necessitates carrying the casket into the road on which the hearse is parked and the rear door is therefore not ordinarily used during the course of a funeral for either placing the casket into the hearse or removing it from the hearse.

Because of many practical considerations, a casket is almost always placed into a hearse with the feet of the body foremost. With side service hearses as heretofore constructed, if the casket is placed into the hearse feet first, it becomes necessary to remove the casket from either of the side doors of the hearse head first. However, under many circumstances, and sometimes in accordance with custom, a body in a casket is carried with the head foremost. Therefore, if the body is placed in a hearse feet first and it is desired to remove the casket from the hearse and carry it feet foremost, it becomes necessary for the pall bearers to turn casket around after removing it from the hearse. This procedure of turning a casket around at the side of a hearse is awkward and sometimes dangerous. For example, almost all cemeteries have narrow roads and an incline directly at the side of the road. Thus the procedure of turning a casket around at the side of the hearse in the cemetery is very dangerous since the pallbearers have to walk backwards up the incline at the side of the road and in wet weather or when the ground is covered with ice and snow, the possibility of a mishap is even greater. This danger is even more pronounced in the case of rural cemeteries where in many instances it is impossible to drive the hearse into the cemetery. Under these conditions, the hearse must be parked on the road, which in most instances is a rural one with ditches at either side, and the casket must be turned around in a ditch or a snow bank or under other hazardous conditions. The fact that side service hearses

2

of conventional design necessitate the cumbersome and dangerous procedure of turning the casket around at the side of the hearse has resulted in many funeral directors looking upon side service hearses with much disfavor.

There is also associated with side service hearses of conventional design another feature which makes for unnecessary confusion and inconvenience during the funeral. In the conventional hearse, the track arrangement and table are designed such as to permit the table to be withdrawn with its forward end first through one of the side door openings and with such construction, the table is locked while in transit at a position somewhat centrally, in a longitudinally direction, of the hearse compartment. With such an arrangement the only space available for the placing of flowers is on top of and along each side of the casket. Therefore, when it becomes necessary to remove the casket from the hearse, either at the church or at the cemetery, the side doors must be opened first to remove the flowers at each side of the casket so that the casket may be withdrawn.

25 It is an object of this invention to provide a hearse construction which enables removal of a casket from a hearse either head first or feet first regardless of the position in which the casket is placed into the hearse.

30 It is furthermore an object of the present invention to provide a track arrangement for a side service hearse which permits removal of a casket from the side door openings either head first or feet first without in any way modifying the more or less standard dimensions of a conventional side service hearse.

35 40 A further object of the invention is to produce a construction for a side service hearse which provides a flower compartment at the rear end of the casket compartment which eliminates the necessity for placing the flowers along the sides of the casket.

More specifically, the invention contemplates a side service hearse having a vehicle seat which is movable forwardly from the normal driving position so as to increase substantially the effective length of the casket compartment when it is desired to remove the casket from the hearse. The track and table arrangement of our hearse are designed to permit the table to be moved forwardly from a normal position of transit and when in such forwardly shifted position, to be pivoted so that the rear end of the table can be guided to a position projecting out of the door opening at either side of the hearse. In a con-

ventional hearse, the wheel base is approximately 155 to 160 inches and the width of the casket compartment varies from about 50 to 55 inches in width and from about 120 to 125 inches in length. The casket table is approximately 86 inches long and the side door openings are approximately 91 inches wide. The hearse construction of our improved design enables removal of the casket either head or feet first without involving a departure from these basic dimensions. In other words, an important feature of our hearse construction is that it can be incorporated on any frame and chassis arrangement of standard hearse design.

In the drawings:

Figure 1 is a perspective view with parts broken away of a hearse embodying our invention; the casket table being shown in the normal position of transit.

Figure 2 is a somewhat diagrammatic plan view of our hearse showing the manner in which the casket may be removed head first, that is with the front end of the casket table foremost.

Figure 3 is a view similar to Figure 2 showing removal of the casket feet first.

Figure 4 is a fragmentary perspective view, with parts broken away, showing the stop mechanism for the hearse table, the front stop being shown in the engaged position and the rear stop in the disengaged position.

Figure 5 is a diagrammatic view of the stop arrangement with both stops shown in the engaged positions.

Figure 6 is a sectional view through the platform of the hearse compartment showing both stops for the casket table in the released position.

Figure 7 is a sectional view taken along the lines 7—7 in Figure 4.

Figure 8 is an enlarged fragmentary sectional view of the track on the platform of the casket compartment taken substantially along lines 8—8 in Figure 4.

Figure 9 is a sectional view taken along lines 9—9 in Figure 2.

Referring to the drawings, particularly to Figure 1, there is shown a conventional hearse body 10 having front and rear side doors 12 and 14 at each side thereof which overlap along their free edges to provide a wide opening at each side of the hearse which is defined at its front end by a front door pillar 16 and at its rear end by a rear door pillar 18. Within the hearse body there is mounted a conventional vehicle seat 20 which is shiftable from the normal driving position shown in Figure 1 forwardly to a position adjacent the steering wheel 22. The floor of the casket compartment comprises a platform 24 which extends at its front end just to the rear of seat 20 when in normal driving position. The rear end of platform 24 extends to the door opening 26 at the rear end of the hearse. The casket compartment is generally defined by the length and width of platform 24. At the rear portion of the casket compartment its width is somewhat decreased by housings 28 at each side which enclose the rear wheels of the vehicle. The rearward position of the rear door pillars 18 and therefore the size of the side door openings is determined by the location of the front end of housing 28.

With the exception of the forwardly movable front seat 20, the construction thus far described is more or less conventional and is dimensioned

in accordance with standard hearse design as set forth above.

Platform 24 includes a floor 30 having a plurality of ball bearings 32 thereon which are arranged to support a casket table 34 for rolling movement on the platform. Table 34 is in turn provided with a plurality of cylindrical rollers 36 for rollably supporting a casket 31. The movement of table 34 on floor 30 is controlled by a track arrangement which comprises a longitudinal groove 38 on floor 30 and angle brackets 40 or the like mounted on the under side of table 30 which provide a guideway for rollers 42 which are securely mounted on the under side of table 34 by shafts 44. Groove 38 and brackets 40 extend centrally of platform 24 from the rear end thereof forwardly to a point 46 spaced rearwardly of the front end of the platform. Table 34 is provided with two rollers 42 on the under side thereof, the spacing of which will be presently described.

Floor 30 is also provided with a pair of transverse grooves 48 and 50 which extend from groove 38 and converge toward each of the side door openings. On the under side of table 30 angle members 52 are associated with each of the grooves 48 and 50 to define transverse guideways for rollers 42. Grooves 48 and 50 are arcuate in shape, groove 48 defining a circumferential path generated by a radius having its center at the front end 46 of groove 38. Rollers 42 are spaced longitudinally of table 34 such that when the front roller is disposed at the front end 46 of groove 38 the rear roller is aligned with the transverse track portions 48. The front roller 42 is spaced rearwardly of the front end of table 34, a distance approximately equal to the distance through which seat 20 moves in a forwardly direction from the normal driving position shown in Figure 1 to the position shown in Figure 3.

To facilitate the proper movement of table 34 along the desired track sections, there is provided on the under side of floor 30 a front stop 54 engageable with front roller 42 and a rear stop 56 engageable with rear roller 42. Stop 54 is arranged adjacent the intersection of track 38 and track 50 so that when the front roller 32 abuts against the front face of stop 54, it is positioned in track 38 just ahead of tracks 50. Rear stop 56 is positioned to engage rear roller 42 when the front roller is engaged by stop 54. Stop 54 is formed integrally with a bushing 55 which is fixedly mounted on a shaft 58 extending transversely of platform 24. An operating handle 60 is fixed at each end of shaft 58. Stop 56 is fixed on a shaft 62 which likewise extends transversely of platform 24. An intermediate shaft 64 is supported on the under side of floor 30 by brackets 66. At one end shaft 64 is provided with a pair of bushings 68 and 70, bushing 68 being fixed to the shaft and bushing 70 being rotatable on the shaft. The adjacent side faces of bushing 68 and 70 are fashioned to provide a lost motion connection 72 which permits rotation of bushing 68 through 90° before engaging bushing 70. Shafts 58 and 64 are interconnected by a link 74 connected at one end to a crank arm 76 on shaft 58 and at the other end to an offset crank arm 78 on bushing 68. Shafts 62 and 64 are interconnected by a link 80 secured at one end to a crank arm 82 on bushing 70 and at the other end to a crank arm 84 fixed on shaft 62.

These crank arms and links are arranged such that in the released position stops 54 and 56 ex-

tend horizontally and are free of rollers 42 as is shown in Figure 6. When handle 60 is turned 90° in a clockwise direction, that is, to the position shown in Figure 4, stop 54 is rotated to a vertically downwardly extending position and an oppositely disposed stop member 86 on bushing 55 engages the front face of front roller 42 and shifts table 34 rearwardly to a position where front roller 42 is aligned with tracks 50. The rotation of crank arm 78 from the position shown in Fig. 6 to the position shown in Fig. 4 is, by reason of the lost motion connection 72, ineffective to rotate crank arm 82 and stop 56 therefore remains in the horizontal position. If handle 60 is then rotated 180° in a counter-clockwise direction, both stops 54 and 56 are rotated to the engaged position shown in Figure 5. It will be appreciated, of course, that stops 54 and 56 may be operated by means other than those shown. They may for example be electrically actuated.

The normal position of table 34 while in transit is the locked position illustrated in Figures 1 and 5. In this position, the front end of the table is spaced just to the rear of seat 20 and the rear end of the table is spaced forwardly a substantial distance from the rear door opening 26. A pair of doors 88 are hinged along vertical edges to housings 28 at each side of the hearse, doors 88 being positioned such that in closed position, they form a compartment 90 just to the rear of table 34 in which flowers may be arranged. It will be appreciated that with table 34 in the normal position for transit, the basic dimensions of the standard hearse design permits compartment 90 to have a length equal approximately to one quarter the length of the casket compartment. The rear portion of track 38 is closed by a filler strip 92 which slidably engages in track 38 so that flowers and the like will not fall into the track.

Assuming that table 34 is in the normal position for transit, that is, in a position illustrated in Figure 1 with rollers 42 locked in place by stops 54 and 56 as illustrated in Figure 5, and it is desired to remove the casket head first, that is with the front end of table 34 projecting out of one of the side door openings, handle 60 is pivoted 180° to the position shown in Figure 4. In this position, front roller 42 shifted rearwardly into alignment with tracks 50 by stop member 86 and table 34 may be pivoted towards either side of the hearse so that front roller 42 follows one of the tracks 50, that is, from the position shown by broken lines to the position shown by solid lines in Figure 2.

If it is desired to remove the casket feet first, that is, with the rear end of the table projecting out of one of the side doors, then handle 60 is pivoted from the position shown in Figure 5 to the position shown in Figure 6 so that rollers 42 are free of both stops. Seat 20 is then shifted forwardly to the position shown in Figure 3 and the effective length of the casket compartment is thereby substantially increased. Table 34 is then shifted forwardly to a position where front roller 42 is at the front end 46 of track 38. In this position rear roller 42 is aligned with tracks 48 and the table may be pivoted about front roller 42 so as to guide the rear roller 42 along either of the tracks 48. I have found that with conventional hearses that if seat 20 is moved forwardly approximately 14 inches, sufficient clearance is provided to enable the rear end of table 34 to swing through the door opening at either side of the hearse without interference from the rear door pillars 18. At the same time the

front end of the casket table swings away from the rear side of the forwardly moved seat towards the doors on the opposite side of the hearse.

It will thus be seen that I have provided a hearse construction which enables a casket to be removed from a hearse either end first without altering any of the basic dimensions of a standard hearse design. The invention provides a hearse which is more convenient to use and which enables funerals to be conducted with much less confusion and without the danger associated with the operation of turning the casket around at the side of the hearse. Furthermore, it will be observed that by positioning the casket table while in transit at the front end of the casket compartment ample space is provided at the rear end of the casket compartment to form a flower compartment accessible through the door at the rear end of the hearse. This flower compartment avoids the necessity of placing the flowers along side the casket and simplifies the funeral procedure considerably since the flowers may be removed either simultaneously with, prior to or subsequent to the removal of the casket from the hearse.

We claim:

1. In a conventional side service hearse having a platform in the casket compartment supporting a casket table, the combination of a vehicle seat positioned forwardly of the casket compartment, said seat being shiftable forwardly to temporarily increase the effective length of said casket compartment, a main track on said platform extending in a direction longitudinally of the casket compartment, said track having branch portions extending transversely of said casket compartment toward the door openings at each side of said hearse, a front and rear track follower on said table engaged in said track, said table being movable forwardly in said track, when said seat is shifted forwardly, to a position where the front end of the table occupies the space normally occupied by said seat and said rear track follower is aligned with said branch track portions, said table when in said forward position being pivotable about the front track follower and within the confines of said casket compartment to move the rear track follower along either of said branch track portions and thereby project the rear end of said table outwardly through the door opening at either side of the hearse.
2. The combination set forth in claim 1 wherein in said branch track portions are of arcuate contour in horizontal section.
3. The combination set forth in claim 1 wherein in said branch track portions define a circumferential path generated by a radius struck from a point on the longitudinal axis of said main track.
4. In a conventional side service hearse having a platform in the casket compartment supporting a casket table, the combination of a vehicle seat positioned forwardly of the casket compartment, said seat being shiftable forwardly to temporarily increase the effective length of said casket compartment, track means on said platform, guide members on the under side of said table movable in said track means for guiding the movement of said table in said casket compartment, said track means and guide members being arranged such that when said seat is shifted forwardly, said table is movable forwardly along said track means to a position where the table extends longitudinally of the casket compartment and the front end of the table extends into the additional space

at the front end of said casket compartment provided by the forward movement of said seat, said guide members being spaced longitudinally of said table, the foremost guide member comprising a pivot engaged in said track for pivoting said table in a horizontal plane on said platform, and means for locking said front guide member in a longitudinally fixed position in said track when the table is shifted to said forward position, said track extending forwardly sufficiently close to said seat and said front guide member being spaced forwardly of the longitudinal center of said table to enable pivoting the table about said front guide member from said forward position to a position wherein the rear end of the table projects outwardly through the door opening at either side of the hearse while the door opening at the other side of the hearse remains closed.

6. In a conventional side service hearse having a platform in the casket compartment supporting a casket table, the combination of a vehicle seat positioned forwardly of the casket compartment, said seat being shiftable forwardly to temporarily increase the effective length of said casket compartment, a main track on said platform extending in a direction longitudinally of the casket compartment, said main track having a pair of branch portions extending toward the door openings at each side of said hearse, one branch track portion in each pair being spaced forwardly of the other, a front and back track follower on the under side of said table engaged in said track, said front track follower being movable along either of said forward branch tracks to guide the front end of said table to a position extending outwardly through either of said door openings, said table being movable forwardly in said track, when said seat is shifted forwardly, to a position where the front end of the table occupies the space normally occupied by said seat and where 40 said rear track follower is aligned with said branch track portions, said table when in said forward position being pivotable about the front track follower and within the confines of said casket compartment to move the rear track follower along either of said branch track portions and thereby project the rear end of said table outwardly through the door opening at either side of the hearse, each pair of said branch track portions forming a generally V-shaped track arrangement, the tracks in each pair converging toward the door opening at each side of said hearse.

6. In a conventional side service hearse having a platform in the casket compartment supporting a casket table, the combination of a vehicle seat positioned forwardly of the casket compartment, said seat being shiftable forwardly to temporarily increase the effective length of said casket compartment, a main track on said platform extending in a direction longitudinally of the casket compartment, said main track having a pair of branch portions extending toward the door openings at each side of said hearse, one branch track portion in each pair being spaced forwardly of the other, a front and back track follower on the under side of said table engaged in said track, said front track follower being movable along either of said forward branch tracks to guide the front end of said table to a position extending outwardly through either of said door openings, said table being movable forwardly in said track, when said seat is shifted forwardly, to a position where the front end of the table occupies the space normally occupied by said seat and where said rear track follower is aligned with said branch track portions, said table when in said forward position being pivotable about the front track follower and within the confines of said casket compartment to move the rear track follower along either of said branch track portions and thereby project the rear end of said table outwardly through the door opening at either side of the hearse, the rear track of each of said branch track portions defining a circumferential path generated by a radius struck from a point on the longitudinal axis of said main track whereby said table pivots about a fixed point when manipulated to swing the rear end thereof towards the door opening at either side of the hearse.
